UNITED STATES PATENT OFFICE.

CLARENCE A. WETZELL, OF STERLING, ILLINOIS.

MECHANICAL TOY.

Application filed April 23, 1923. Serial No. 633,917.

This invention relates to mechanical toys of the kind which are adapted to be propelled or moved along the floor to produce the desired mechanical effect.

Generally stated, the object of the invention is to provide a simple and comparatively inexpensive mechanical toy having a figure thereon which appears to be propelling the toy when it is drawn along the floor.

It is also an object to provide certain details and features of construction and combinations tending to increase the general efficiency and the desirability of a mechanical toy of this particular character.

To the foregoing and other useful ends the invention consists in matters hereinafter set forth and claimed and shown in the accompanying drawings in which—

Figure 1 is a plan of a mechanical toy embodying the principles of the invention.

Figure 2 is a side elevation of said toy.

Figure 3 is a plan view showing the trailer in position behind the toy vehicle.

Figure 4 is a side elevation of the toy as shown in Figure 3.

As thus illustrated, the invention comprises a support or chassis 1 having a slot 2 at the front end thereof for the single wheel 3, and having its rear end provided with an axle 4 carried by the wheels 5, these wheels being of any suitable character. As shown in Figures 1 and 2, the box body 6, which may form the trailer, as hereinafter explained, is secured to the support 1 by a single screw 7, and has its under side provided with a transverse bolster 8 which engages the rear of the support 1 to help position the box on the support. The front end 40 of the box or body 6 has a screw eye 9 inserted therein. The rear end of said box has a couple of spare wheels 10 held in place thereon by a single screw 11, in the manner shown.

The forward portion of the toy has a fixed cylindric portion 12 which forms the body or torso of the toy figure. The upper end of the cylindric body 12 has a round head 13, and is provided with outstretched

50 arms 14 pivoted on the body at 15, the hands 16 of the arms having a spacer 17 between them. A wire 18 extends downward from the spacer 17 to the support 1, to hold the arms in raised and outstretched position.

55 The two legs of the figure are articulated at the knees, and each leg comprises the sec-

tion 19 which is pivoted on the side of the body 12 at 20, and the section 21 which is pivoted on the section 19 at 22, the feet 23 being disposed at each side of the forward 60 portion of the support 1 of the toy, so that the legs are at opposite sides of the slot 2 of the projecting front end portion of the body-like support. It will be seen that the single wheel 3 has a crank 65 axle 24, the two cranks being disposed oppositely, so that when one crank is up the other is down. These two cranks are engaged by the feet 23 of the toy figure, so that when one foot is down the other is up. 70 A string 25 may be attached to the front end of the toy, ahead of the front wheels, to propel it along the floor. This operates the articulated legs of the figure, and the effect is that the figure has the appearance 75 of propelling the toy, just as a boy riding a velocipede.

Now to change the toy, and to bring the trailer into position behind the wheel support 1, all that is necessary is to simply remove the screws 7 and 11, and to remove the box 6 from the support. The screws 7 and 11 are then inserted through the spare wheels 10 and into the screw holes 26 in the ends of the bolster 8, as shown in Figures 80 3 and 4, so that the two wheels are thus secured in place to support the box 6 on the floor. Then the screw eye 9 is coupled to the hook 27 on the rear end of the support 1, as shown in Figures 3 and 4, and the toy 85 is then ready for operation with the trailer in position behind. Thus the two screws 7 and 11 serve the double function of holding the box and spare wheels in position, and of forming axles for the spare wheels when 90 the trailer is in position behind the toy. 95

It will be understood that the parts can all be made of wood, or other suitable material, except the cranks 24 and the screws and other portions which can be made of wire or other metal. The toy is easily convertible into a trailer, as shown, and is easily restored to the condition shown in Figures 1 and 2, in a manner that will be readily understood.

With the exception of the screws 7 and 11 it will be seen that the instrumentalities for converting the body 6 into a trailer are inoperative while the body is in position on the wheeled support. When the body is in the position shown in Figures 1 and 2, the screw 7 functions to hold the body in

place, and the screw 11 functions to support the two wheels 10 on the rear end of the body. The connecting means 9 on the front end of the body are inoperative, when the 5 body is fastened on the wheeled support, and at such time the engaging means 27 is also inoperative, and in this condition of the toy the wheels 10 are inoperative and are merely carried by the body as spare 10 wheels.

Of course, the toy may be used without removing the box from the body 1 which is horizontal and which forms the chassis of the vehicle, and in that event the toy 15 figure will appear to be propelling the vehicle with said box 6 in position to carry a load of sand or the like therein and in rear of the figure, which latter has the torso 12 thereof in the plane of the box, and 20 has the pivots 20 disposed in such position that the knees of the legs are always above the top of the body 1 forming the chassis of the vehicle, in the manner shown and described. Thus the toy has the appearance 25 of a truck for commercial purposes, for carrying a load of sand or other materials in the box thereof, and when the toy is pulled along the floor the little figure in front has the appearance of furnishing the 30 power for propelling the vehicle with the box in the rear thereof in which a load of sand or other materials can be carried.

Of course, the toy can be used either with or without the box 6, as the latter can be 35 left off, if so desired, and the toy can be pulled along the floor by the pull connection 25 without having the box in position in rear of the figure, if it is desired to use the toy without the box or load carrier, but 40 in either case the figure has the appearance of both propelling and steering the figure.

What I claim as my invention is—

1. In a toy, the combination of (1) a 45 wheeled support, (2) a body removably secured thereon, detachable therefrom to form a trailer therefor, and (3) instrumentalities including means to form a draft connection and means whereby to support the body on the floor, carried by the toy and adapted 50 for converting said body into a trailer for said toy, when the body is removed from the wheeled support, so that the one and the same body can serve either as a carrier on the wheeled support, or as a trailer behind.

55 2. A structure as specified in claim 1, said instrumentalities comprising connecting means for the front end of the body, means under the body and on the support to engage said connecting means, forming said draft connection, a couple of spare wheels forming part of said means to support the body on the floor, a screw for mounting said spare wheels on the rear end of the body, and a screw for attaching the 60 body to the wheeled support, said screws

being removable and serving as axles for the spare wheels when the trailer is coupled to the rear end of the wheeled support, whereby the two screws are necessary in either condition of the toy. 70

3. A structure as specified in claim 1, said instrumentalities comprising a couple of screws inserted in the body, and a couple of spare wheels which utilize said screws as axles when the screws are removed and inserted in position to form the axles of the trailer, forming said means to support the body on the floor, said screws having other positions on the toy when not in use as axles. 75

4. A structure as specified in claim 1, in combination with means at the front of 80 said support to simulate propelling means for the toy, in either condition thereof, whereby said simulated propelling means are operative with said body either on the 85 wheeled support, or behind as a trailer.

5. A structure as specified in claim 1, in combination with a toy figure sitting on said support in front of said body and adapted 90 to simulate propelling means for the toy, in either condition thereof, whereby said figure is not disturbed by the use of said instrumentalities to form the trailer.

6. A structure as specified in claim 1, said body having a front wheel, and means 95 simulating propelling means for said wheel, operative with said body in either position thereof.

7. A pull toy comprising a horizontal rigid body, two wheels for the rear end of 100 said body, a single wheel in a slot in the front end portion of said body, the axes of all said wheels being in fixed relation to each other, said body and wheels forming the chassis and running gear of a vehicle having a box mounted on the rear end of 105 said body, between the rear wheels, a member forming the torso of a toy figure, said member fixed at its lower end on said body in front of said box, so that the torso 110 is rigid with said vehicle body, a head on said torso, cranks for said front wheel, a crank axle rigid with said cranks and wheel and extending transversely through said body, jointed legs having feet engaging said cranks at opposite sides of said slot, means forming a transverse pivot axis in the base of said torso, for said legs, so that the legs are spaced apart by the base of 115 said torso, arms for said torso, and means attached to the forward end of said body 120 for pulling said toy along the floor to cause said cranks to actuate said legs, whereby the toy figure appears to be propelling the vehicle with said box in position to carry a load in rear thereof, the feet being movable up and down at opposite sides of the front end portion of the body. 125

8. A structure as specified in claim 7, the top of said body being level, so that the 130

box and the torso are in the same plane, so that the knees of said legs are above the top of said body, the attachment of the torso to the body being independent of the pivots for the legs, so that with the legs taken off the torso would remain rigidly in place.

9. A structure as specified in claim 7, comprising an upright member fixed on said body and provided at its upper end with a cross piece serving as a support for and spacer between the hands of said arms, said body having a slot in front of said upright member for said front wheel.

10. A pull toy comprising a horizontal body, two wheels for the rear end of said body, a single wheel disposed in the front end portion of said body, so that the front end extends forward of said front wheel, said body and wheels forming the chassis and running gear of a vehicle, the axes of said wheels being in fixed relation to each other, a rigid member forming the torso of a toy figure fixed at its lower end on said body, so that the torso is rigid with said vehicle body, a head on said torso, a crank axle extending through the front end portion of said body and having cranks for rotating said front wheel, jointed legs having feet engaging said cranks, means forming a transverse pivot axis in the base of said torso, for said legs, so that the legs are spaced apart by the base of said torso, arms for said torso, and means connected to said front end ahead of said front wheel for pulling said toy along the floor to cause said cranks to actuate said legs, whereby the toy figure appears to be propelling the vehicle, the feet being movable up and down at opposite sides of the front end portion of the body.

11. A structure as specified in claim 10, in combination with a crosspiece serving as a spacer between the hands of said arms and an upright member rigid with said body and supporting said crosspiece, whereby the figure has the appearance of both propelling and steering the toy.

12. A structure as specified in claim 10, the lower sections of said legs being disposed

at opposite sides of said body, and the upper sections being pivoted on the side of said torso so that the knees of the legs are higher than the top of the body, and higher than the pivot of the legs on the lower end of the torso, and means extending upward between the knees to support said arms in position, whereby the figure has the appearance of both propelling and steering the vehicle.

13. In a toy, the combination of (1) a wheeled support, (2) a body removably secured thereon, and (3) instrumentalities carried by the toy and adapted by readjustment thereof for converting said body into a trailer for said toy, when the body is removed from the wheeled support, so that the one and the same body can serve either as a carrier on the wheeled support, or as a trailer behind, said instrumentalities comprising connecting means for the front end of the body, means under the body and on the support to engage said connecting means, a couple of spare wheels, a screw for mounting said spare wheels on the rear end of the body, and a screw for attaching the body to the wheeled support, said screws being removable and serving as axles for the spare wheels when the trailer is coupled to the rear end of the wheeled support, whereby the two screws are necessary in either condition of the toy.

14. In a toy, the combination of (1) a wheeled support, (2) a body removably secured thereon, and (3) instrumentalities carried by the toy and adapted by readjustment thereof for converting said body into a trailer for said toy, when the body is removed from the wheeled support, so that the one and the same body can serve either as a carrier on the wheeled support, or as a trailer behind, said instrumentalities comprising a couple of screws inserted in the body, and a couple of spare wheels which utilize said screws as axles when the screws are removed and inserted in position to form the axles of the trailer, said screws having other positions on the toy when not in use as axles.
